Attorneys

UNITED STATES PATENT OFFICE

JOHN F. DOHRWARDT, OF SOUTH MILWAUKEE, WISCONSIN, ASSIGNOR TO LINE MATERIAL COMPANY, OF SOUTH MILWAUKEE, WISCONSIN, A CORPORATION OF WISCONSIN

EXPULSION FUSE

Application filed June 12, 1929. Serial No. 370,258.

My invention relates to expulsion fuses of the type in which a fuse link extends from one of the fuse terminals to a point beyond the other fuse terminal through a gas-tight tube member of insulating material, back-
wardly along the outer face of which tube member the link is doubled for its connection to said other terminal, said tube member or a suitable extension thereof being open to the atmosphere at or beyond the point where the fuse link is doubled back, whereby the gases generated in the tube upon the rupture or consumption of the link therein are permitted to escape freely from the fuse box.
It is one of the objects of my invention to provide a new and improved form and arrangement of parts in an expulsion fuse of this type by which an effective barrier is provided against the entrance of any gas into the fuse box after its escape from the end of the tube, such barrier being arranged preferably to extend out some little distance from the face of the tube so as to increase materially the distance which the gas would have to travel to get to the fuse terminal into effective arcing position if a small quantity of the gas might seep into the box from the outer end of the tube structure or from the transversely opening fuse port in the side of the tube structure.

It is another object of my invention to improve devices of this type in sundry details hereinafter pointed out. The preferred means by which I have accomplished my several objects are illustrated in the drawing and are hereinafter specifically described. That which I believe to be new and desire to cover by Letters Patent is set forth in the claims.

In the drawing,—

Fig. 1 is a central vertical section through my improved device, certain of the parts being shown in side elevation;

Fig. 2 is a bottom end view of the device as shown in Fig. 1, certain of the parts being

broken away at one side of the device for better illustrating the construction; and

Fig. 3 is a central vertical section through the bottom portion of the tube structure and the barrier.

Referring now to the several figures of the drawing, in which corresponding parts are indicated by the same reference characters, 10 indicates the fuse box formed of porcelain or other suitable insulating material, having a 55 cover or lid 11 hingedly connected therewith at one side in position for closing the side of the box, such lid or cover 11 being adapted to swing outwardly and downwardly about trunnions 12 forming part of the hinge means. 60 The arrangement is such that the cover 11 is adapted to be swung downwardly into vertical position so as to hang from the trunnions 12. The cover or lid 11 in the construction shown is formed of rubber or composition. 65 The box 10 in the construction shown is provided with bolts 13 extending from its rear face for connection to any suitable support.

Upon the front face of the rear wall of the box 10, I have provided connectors in the 70 form of spring clips or yokes 14 mounted in position by means of screws 15 secured by means of screw threads in retainer blocks 16 mounted in the rear wall of the box. The screws 15 also hold in position plates 16^a 75 which have line terminals 17 formed integrally therewith opposite openings 18 in the side walls of the box. The side walls of the box above the openings 18 are provided with extensions 19 serving to protect the openings 80 18 more or less completely against the entrance of water or other foreign matter. On the front face of the rear wall of the box, I have provided a barrier plate 20 extending forwardly between the line terminals 17. 85

Upon the inner face of the cover plate 11, I have provided fuse terminals 21 and 22 in position to engage between the arms of the spring clips 14 when the cover plate is in closed position. In the construction shown, 90

the fuse terminals 21 and 22 are secured movably in position upon the front face of the cover plate 11 by means of screws 23 engaging notched lugs 24 formed integral-
 5 ly with the terminals 21 and 22, the ar-
 rangement being such that the terminals 21 and 22 are movable freely from side to side with respect to the cover plate 11. A tube 25 formed of insulating material ex-
 10 tends from the terminal 21 through an opening in the terminal 22 to a point located within an opening 26 in the bottom wall of the box 10, the opening 26 in the construction shown being in the form of a notch open at
 15 its forward end. Upon the lower end of the tube 25 below the fuse terminal 22, I have mounted a barrier plate 27 which extends outwardly from the face of the tube 25, being held fixedly in position by means of a set
 20 screw 28. Upon the extreme lower end por-
 tion of the tube 25, I have provided a second tube 29 formed of insulating material, such tube 29 being secured in position upon the end of the tube 25 by means of screw threads, as is
 25 clearly shown in Fig. 3, such tube member 29 extending downwardly from the box 10 through the opening 26 and being open at its lower end outside of the box. A fuse link 30 of any suitable type is secured at its upper end
 30 to the fuse terminal 21 by means of a cap 31 removably mounted in position by means of screw threads. The fuse link 30 extends from the cap 31 downwardly through the tube
 25 to a point beyond the fuse terminal 22 and
 35 the barrier plate 27, extending outwardly in transverse position through a notch 32 in the side wall of the tube 25 near its lower end. As is best shown in Fig. 3, the bottom face of the barrier plate 27 is provided with a groove
 40 33 along which the fuse link 30 extends so as to permit the face of the plate 27 to fit snugly against the inner face of the bottom end wall of the box 10 for substantially closing the opening 26 about the tube structure comprising
 45 the members 25 and 29. The fuse link 30 is turned backwardly about the barrier plate 27 for connection to the fuse terminal 22 by means of a set screw 34, as is best shown in Fig. 1.
 50 By my improved construction, the line terminals 17 are connected by means comprising the fuse link 30 so long as the cover plate 11 is in closed position as shown in said Fig. 1, the arrangement being such that the fuse link is
 55 connected in series between the wires which extend through the openings 18 into the box for connection with the terminals 17. The arrangement is such that when the cover plate 11 is moved outwardly and downwardly with
 60 respect to the box the fuse terminals 21 and 22 are moved out of engagement with the spring clips 14 so as to break the connection between the line terminals 17. The size of the notch 26 is such that clearance is provided for the
 65 extension tube member 29 for permitting the

swinging movement of such tube member with the cover plate 11 upon an opening operation. This clearance is provided without detriment with respect to the closure of the box by reason of the provision of the barrier plate 27 which effectively closes the opening about the tube member 29.

When it is desired to thread a new fuse 30 in position, the cap 31, the set screw 34, and the tube extension member 29 are all removed, 70 the cover plate having first been turned to its open position. The fuse is then connected at its end portion by means of the cap 31, and the link is folded back about the barrier plate 27 and secured at its opposite end by the set screw 80 34. The extension sleeve 29 is then secured in position bringing the parts to the relative position as shown in Fig. 1, whereupon the cover plate 11 and the parts carried thereby can be 85 swung into operative position.

Not only is the barrier plate 27 effective for closing the opening about the tube structure in the lower end of the box 10, but it is also effective for shunting sidewise any gas which might seep through the opening in the side wall of the tube structure through which the fuse link 30 extends at the upper end of the sleeve member 29. Such gas deflected by the plate 27 from a direct path upwardly toward the terminal 22 would be likely to pass downwardly through the notch 26 without any tendency to enter the box at the joint between the barrier plate 27 and the end wall of the box.

While I prefer to employ the construction substantially as shown in my drawing, it is to be understood that I do not limit the invention to the form as shown except so far as the claims may be so limited by the prior art, it being understood that changes might well be made in the construction without departing from the spirit of my invention.

I claim:—

1. A device of the type described, comprising in combination a fuse box, a line terminal in said box, a second line terminal in said box in spaced relation to said first named terminal, a tube of insulating material extending from said first named terminal to said second terminal and having an opening therefrom at a point beyond said second terminal, a barrier surrounding said tube and extending outwardly from its face at a point between said opening and said second terminal, and a fuse link connected with said first named terminal 110 and extending therefrom through the tube and turned backwardly about said barrier and connected at its turned-back portion with said second terminal.

2. A device of the type described, comprising in combination a fuse box, a line terminal in said box, a second line terminal in said box in spaced relation to said first named terminal, a tube of insulating material extending from said first named terminal to said second 125 terminal,

terminal and having an opening therefrom at a point beyond said second terminal, a barrier surrounding said tube at a point between said opening and said second terminal and serving substantially to close the end of the fuse box about the tube, and a fuse link connected with said first named line terminal and extending therefrom through the tube and turned backwardly about said barrier and connected at its turned-back portion with said second terminal.

3. A device of the type described, comprising in combination a fuse box, a line terminal in said box, a second line terminal in said box in spaced relation to said first named terminal, a tube of insulating material extending from said first named terminal to a point beyond said second terminal, a second tube member of insulating material held removably in position to act as an extension of said first named tube member and opening at its lower end outside of said fuse box, a barrier surrounding one of said tube members and serving substantially to close the end of the box about the tube, and a fuse link connected with said first named line terminal and extending therefrom through said first named tube member and turned backwardly about said barrier and connected at its turned-back portion with said second terminal.

4. A device of the type described, comprising in combination a fuse box, a line terminal in said box, a second line terminal in said box in spaced relation to said first named terminal, a tube of insulating material extending from said first named terminal to a point beyond said second terminal, a second tube member of insulating material removably secured on the end of said first named tube member and opening at its lower end outside of said fuse box, a barrier plate fixedly secured on said first named tube member adjacent to said second tube member and extending outwardly from its face, and a fuse link connected with said first named line terminal and extending through said first named tube member and extending transversely from said tube member at a point above said second tube member and turned backwardly about said barrier plate and connected at its turned-back portion with said second terminal.

5. A device of the type described, comprising in combination a fuse box, a line terminal in said box in spaced relation to said first named terminal, a tube of insulating material extending from said first named terminal to a point beyond said second terminal, a second tube member of insulating material removably secured on the end of said first named tube member and opening at its lower end outside of said fuse box, a barrier plate fixedly secured on said first named tube member adjacent to said second tube member and extending outwardly from its face in position for

closing the end of said fuse box about the tube, and a fuse link connected with said first named line terminal and extending through said first named tube member and extending transversely from said tube member at a point above said second tube member and turned backwardly about said barrier plate and connected at its turned-back portion with said second terminal.

6. A device of the type described, comprising in combination a fuse box, a line terminal in said box, a second line terminal in said box in spaced relation to said first named terminal, a tube structure of insulating material extending from said first named terminal with its lower end open outside of the fuse box, a barrier mounted on said tube structure in position for closing about the tube the opening through which the tube projects from the box, and a fuse link connected with said first named line terminal and extending through said tube structure and turned backwardly about said barrier and connected at its turned-back portion with said second terminal.

7. A device of the type described, comprising in combination a fuse box, a line terminal in said box, a second line terminal in said box in spaced relation to said first named terminal, a tube structure of insulating material extending from said first named terminal with its lower end open outside of the fuse box, a barrier mounted on said tube structure in position for closing about the tube the opening through which the tube projects from the box, and a fuse link connected with said first named line terminal and extending through said tube structure and outwardly through a small opening in the side of the tube structure at a point below said barrier and turned backwardly about said barrier and connected at its turned-back portion with said second terminal.

8. A device of the type described, comprising in combination a fuse box, a line terminal in said box, a second line terminal in said box in spaced relation to said first named terminal, a tube structure of insulating material extending from said first named terminal with its lower end open outside of the fuse box, a barrier mounted on said tube structure in position for closing about the tube the opening through which the tube projects from the box, and a fuse link connected with said first named line terminal and extending through said tube structure and outwardly through a small opening in the side of the tube structure at a point within the fuse box below said barrier and turned backwardly about said barrier and connected at its turned-back portion with said second terminal.

9. A device of the type described, comprising in combination a fuse box, a line terminal in said box in spaced relation to said first named ter-

5 minal, a tube of insulating material extending from said first named terminal to a point beyond said second terminal, a second tube member of insulating material removably secured on the end of said first named tube member and opening at its lower end outside of said fuse box, a barrier plate fixedly secured on said first named tube member adjacent to said second tube member and extending outwardly from its face in position for closing the end of said fuse box about the tube, and a fuse link connected with said first named line terminal and extending through said tube structure and outwardly 10 through a notch in the lower end of said first named tube member below said barrier substantially at the upper end of said second tube member and turned backwardly about said barrier and connected at its turned-back portion with said second terminal.

10. A device of the type described, comprising in combination a fuse box, a line terminal in said box, a second line terminal in said box in spaced relation to said first named terminal, a tube of insulating material extending from said first named terminal to a point beyond said second terminal, a second tube member of insulating material removably secured on the lower end of said 15 first named tube member and projecting from the fuse box through an opening in the lower end of the box, a barrier plate fixedly secured on said first named tube member above said second tube member and extending outwardly from its face in position for closing the end of the fuse box about the first named tube member, and a fuse link connected with said first named line terminal and extending through said first named tube 20 member and outwardly through a notch in the lower end of said first named tube member at a point located within the opening through which the second tube member projects from the fuse box and turned backwardly about said barrier plate and connected at its turned-back portion with said 25 second terminal.

11. A device of the type described, comprising in combination a fuse box, a cover plate hingedly connected with said box at its lower end, a fuse terminal mounted on the inner face of said cover plate near its upper end, a second fuse terminal mounted on the inner face of said cover plate near its lower 30 end, a tube structure of insulating material extending from said first named fuse terminal past said second fuse terminal and projecting downwardly from the fuse box through a notch in the lower end of the box of such size as to provide clearance for the end of said tube structure when the cover plate is swung to open position, a barrier mounted on said tube structure for closing said notch about said tube when the cover 35 plate is in operative closing position, and

a fuse link extending from said first named terminal through said tube structure and about said barrier to said second terminal.

12. A device of the type described, comprising in combination a fuse box, a cover plate hingedly connected with said box at its lower end, a fuse terminal mounted on the inner face of said cover plate near its upper end, a second fuse terminal mounted on the inner face of said cover plate near its lower end, a tube structure of insulating material extending from said first named fuse terminal through an opening in said second fuse terminal and projecting downwardly from the fuse box through a notch in the lower end of the box of such size as to provide clearance for the end of said tube structure when the cover plate is swung to open position, a barrier mounted on said tube structure for closing said notch about said tube when the cover plate is in operative closing position, and a fuse link extending from said first named terminal through said tube structure and about said barrier to said second terminal. 70 75 80 85 90

13. A device of the type described, comprising in combination a fuse box, a cover plate hingedly connected with said box at its lower end, a fuse terminal mounted on the inner face of said cover plate near its upper end, a second fuse terminal mounted on the inner face of said cover plate near its lower end, a tube structure of insulating material extending from said first named fuse terminal through an opening in said second fuse terminal and projecting downwardly from the fuse box through a notch in the lower end of the box of such size as to provide clearance for the end of said tube structure when the cover plate is swung to open position, a barrier mounted on said tube structure in engagement with the lower end wall of the box so as to close said notch about the tube and adapted to swing upwardly out of engagement with said end wall when the cover plate is moved to open position, and a fuse link extending from said first named terminal through said tube structure and about said barrier to said second terminal. 95 100 105 110 115

14. A device of the type described, comprising in combination a fuse box, a cover plate hingedly connected with said box at its lower end, a fuse terminal mounted on the inner face of said cover plate near its upper end, a second fuse terminal mounted on the inner face of said cover plate near its lower end, a tube of insulating material extending from said first named fuse terminal through an opening in said second fuse terminal, an extension tube member of insulating material removably secured on said first named tube member and projecting downwardly from the fuse box through a notch in the lower end of the box of such size as to provide clearance for the extension member 120 125 130

when the cover plate is swung to open position, a barrier mounted on said first named tube member above said extension for closing said notch about said tube when the cover plate is in operative closing position, and a fuse link extending from said first named terminal through said first named tube member and outwardly through a notch in the side wall at the end of said first named tube member and doubled back about said barrier to said second terminal.
